FIGURINE FOR DISPLAYING AN ADVERTISE- MENT OR THE LIKE

Lloyd F. Golkowski, 4921 E. 106th St.,
Garfield Heights, Ohio

Filed Dec. 9, 1959, Ser. No. 58,613

Term of patent 14 years

(Cl. D1—2)

Fig. 2.

Fig. 4.

Fig. 3.

Fig. 1 is a front elevational view of a figurine for displaying an advertisement or the like, showing my new design, the rear being substantially the same as the front shown but with the flattened display panel and the hose connections omitted from the hydrant; Fig. 2 is a right end elevational view thereof; Fig. 3 is a left end elevational view thereof; and Fig. 4 is a top plan view thereof.

I claim:

The ornamental design for a figurine for displaying an advertisement or the like, as shown and described.
